(57) **CLAIM**

The ornamental design for a compact electrical plug, as shown and described.

DESCRIPTION

FIG. 1 is a top left perspective view of a compact electrical plug in an open configuration;

FIG. 2 is a bottom left perspective view of the compact electrical plug of FIG. 1 in an open configuration;

FIG. 3 is a front view of the compact electrical plug of FIG. 1 in an open configuration;

FIG. 4 is a rear view of the compact electrical plug of FIG. 1 in an open configuration;

FIG. 5 is a left side view of the compact electrical plug of FIG. 1 in an open configuration;

FIG. 6 is a right side view of the compact electrical plug of FIG. 1 in an open configuration;

FIG. 7 is a top view of the compact electrical plug of FIG. 1 in an open configuration;

FIG. 8 is a bottom view of the compact electrical plug of FIG. 1 in an open configuration;

FIG. 9 is a top left perspective view of the compact electrical plug of FIG. 1 in a closed configuration;

FIG. 10 is a bottom left perspective view of the compact electrical plug of FIG. 1 in a closed configuration;

FIG. 11 is a front view of the compact electrical plug of FIG. 1 in a closed configuration;

FIG. 12 is a rear view of the compact electrical plug of FIG. 1 in a closed configuration;

FIG. 13 is a left side view of the compact electrical plug of FIG. 1 in a closed configuration;

FIG. 14 is a right side view of the compact electrical plug of FIG. 1 in a closed configuration;

FIG. 15 is a top view of the compact electrical plug of FIG. 1 in a closed configuration;

FIG. 16 is a bottom view of the compact electrical plug of FIG. 1 in a closed configuration; and,

FIG. 17 is an exploded top left perspective view of the compact electrical plug of FIG. 1.
